US0D1060037S

(12) **United States Design Patent** (10) Patent No.: **US D1,060,037 S**
(45) Date of Patent: ** Feb. 4, 2025

(54) **CONTAINER INSERT**

- (71) Applicant: **THE BAZOOKA COMPANIES, LLC**, New York, NY (US)
- (72) Inventors: **Elizabeth Mangold**, Santa Monica, CA (US); **Ashley Leinweber**, New York, NY (US); **Jason Reinbold**, Jersey City, NJ (US); **Anthony Trani**, Brooklyn, NY (US); **Bennet Otto Poepping**, Tuckahoe, NY (US); **David Block**, Brooklyn, NY (US)
- (73) Assignee: **THE BAZOOKA COMPANIES, LLC**, New York, NY (US)
- (**) Term: **15 Years**
- (21) Appl. No.: **29/930,208**
- (22) Filed: **Feb. 28, 2024**

Related U.S. Application Data

- (62) Division of application No. 29/785,097, filed on May 24, 2021, now Pat. No. Des. 1,022,694.
